UNITED STATES PATENT OFFICE.

ALFRED H. OELKERS, OF SPRINGFIELD, MISSOURI.

ROOF CONSTRUCTION.

Application filed February 25, 1925. Serial No. 11,598.

To all whom it may concern:

Be it known that I, ALFRED H. OELKERS, a citizen of the United States, and a resident of Springfield, in the county of Greene and State of Missouri, have invented a new and Improved Roof Construction, of which the following is a full, clear, and exact description.

This invention relates to roof construction, and, while it is primarily designed as a flexible metal roof and combined running board for freight cars, it is also capable of application as a roof for building structures, and, hence, while I shall hereinafter refer to the same as a car roof structure, it is to be understood that I use this language in its broadest possible sense to include any use to which the roof might be put.

The primary object of the invention is to provide a roof construction in which the running board and the roof sheets are combined to form a complete roof of a car, thereby dispensing with the necessity of placing a separate running board over the car roof, as is customary with structures of this kind in general use.

A further object is to secure the running board directly on the carlines and providing an improved joint or joints between the running board and the eaves so as to render the roof absolutely watertight, and yet sufficiently flexible for all purposes.

A further object is to provide a roof of this construction which is strong and durable, which is watertight, which is comparatively simple in construction and in design, and in its labor of assemblage, and which most efficiently performs the functions for which it is intended.

With these and other objects in view, the invention consists in certain novel features of construction and combinations and arrangements of parts which will be more fully hereinafter described and pointed out in the claims.

In the accompanying drawings—

Figure 1 is a view mainly in plan but partly broken away to illustrate parts below;

Figure 2 is an edge view of the construction shown in Figure 1;

Figure 3 is a view in section on the line 3—3 of Figure 1;

Figure 4 is a fragmentary view in transverse section on the line 4—4 of Figure 1;

Figure 5 is an enlarged fragmentary view in transverse section similar to Figure 4 but showing more clearly in detail the roof structure adjacent the running board;

Figure 6 is a perspective view of one of the cap sheets 9;

Figure 7 is a broken fragmentary view in perspective of one of the roof sheets 5;

Figure 8 is a sectional perspective view illustrating a modification;

Figures 9 and 10 are views of details of construction shown in Figure 8.

My improved roof structure includes any desired number of transversely positioned parallel carlines 1, directly supporting at their center a running board 2 and at their outer ends secured to side plates 3. On these side plates 3 I locate and secure my improved eave plates 4 and locate roof sheets 5 between the running board and the eave plates and fitted to both, as will more fully herein-after appear, and these sheets 5 may be made of any desired size and at their longitudinal edges are formed with upwardly projecting flanges or seams 6 between which separator flanges 7 on the carlines 1 project.

Cap bars 8 cover the flanges or seams 6 and the separator flanges 7, and are bolted to the eave plates 4 and the ends of the carlines 1, as indicated at 11. Cap sheets 9 are located under the cap bars 8 at their inner ends and have upwardly projecting curved ends 12 which correspond in shape with the upwardly curved inner ends 13 of the roof sheets 5 and fit under the depending flanges 14 at the side edges of the running board 2.

Above the carlines, secured thereto and running longitudinally of the car under the roof sheets, I provide any desired number of stringers or purlines 10 which give the necessary support to the roof sheets and strengthen the entire roof structure.

I have set forth generally in the above description the several parts of my improved roof structure which I will now describe more in detail.

The running board 2 above referred to, comprises a sheet of proper width and length and having its upper surface roughened, preferably by the provision of knobs or enlargements and nonslippping material. The

intermediate portions of the carlines 1 are enlarged vertically so that their upper flanges 15 provide a horizontal support to which the running board is secured preferably by rivets 16.

The edges of the running board are strengthened by blocks or timbers 17 of any desired length, which are secured by angle bars 18 to the running board, and the depending flanges of the running board are spaced from these timbers or bars 17 sufficient to accommodate the inner ends of the cap bars 8 as well as the upwardly projecting curved overlapping ends of the roof sheets 5 and the cap plates 9.

The eave plates 4 are throughout their greater portion relatively flat or horizontal, and at their outer edges have depending flanges 19 which are riveted or otherwise secured, as shown at 20, to both the plates 3 and the ends of the carlines 1.

The inner edges of the eave plates 4 have upwardly and outwardly bent angular flanges 21, around and under which the outer edges of the roof sheets 5 are curved or projected, as illustrated at 22.

The separator flanges 7 of the carlines 1 are preferably formed integrally with the carlines and project upwardly between the 30 stringers or purlines 10, as clearly shown in Figure 4.

In Figures 8, 9 and 10, I illustrate a modification in which I employ a flashing strip 23 under laterally projecting side portions of the running board 24, between the running board 24 and the bar 17.

In this modification I also provide cap bars 25 corresponding to the cap bars 8 with upwardly curved ends 26 located under 40 the flange 27 of the running board, and I notch the flashing strip as shown at 28 to accommodate and straddle the upwardly projecting flanges of the roof sheets.

Furthermore, it will be noted that I provide notches 29 in the flanges 27 of the running board to engage over the arched upper edges of the cap bars 25. This construction provides a perfect watershed and a strong, durable and flexible construction.

Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. A roof structure including a series of parallel carlines having vertically enlarged intermediate portions, a metal running board secured directly to the enlarged intermediate portions of the carlines, eave plates secured to the outer ends of the carlines, roof plates

secured at their outer ends to the eave plates, and depending flanges at the sides of the running board covering the inner ends of the roof plates and so associated therewith as to permit relative movement of said plates.

2. A roof structure of the character described, comprising transversely positioned carlines, longitudinally positioned stringers or purlines thereon, a running board secured directly to the intermediate portions of the carlines, and roof plates located above the stringers or purlines, and having their inner ends located under the edges of the running board and so associated therewith as to permit relative movement of said plates.

3. A roof structure of the character described, comprising transversely positioned carlines, longitudinally positioned stringers or purlines thereon, a running board secured directly to the intermediate portions of the carlines, and roof plates located above the stringers or purlines and having their inner ends located under the edges of the running board, said running board having depending flanges at its longitudinal edges and said roof sheets having upwardly projecting portions located back of the flanges and under the running board and so associated therewith as to permit relative movement of said plates.

4. A roof structure of the character described, comprising a series of transversely positioned carlines, stringers or purlines secured on the carlines, the intermediate portions of the carlines extended upwardly, a running board secured directly on the upwardly projecting portions of the carlines and having a roughened upper surface, depending flanges at the edges of the running board, blocks or timbers secured to the running board and spaced from the flanges, eave plates secured on the outer ends of the carlines and adapted to be secured to side plates, roof plates located on the stringers or purlines and having upwardly projecting flanges at their longitudinal edges, spacing flanges on the carlines between the flanges of the roof plates, and cap bars located over 100 the adjacent flanges of roof sheets and over the separator flanges, and at their extremities positioned under the running board and secured to the eave plates, respectively.

5. A roof structure of the character described, comprising a series of transversely positioned carlines, stringers or purlines secured on the carlines, the intermediate portions of the carlines extended upwardly, a running board secured directly on the upwardly projecting portions of the carlines and having a roughened upper surface, depending flanges at the edges of the running board, blocks or timbers secured to the running board and spaced from the flanges, eave 110 plates secured on the outer ends of the carlines and adapted to be secured to side plates, roof plates located on the stringers or purlines and having upwardly projecting flanges at their longitudinal edges, spacing flanges on the carlines between the flanges of the roof plates, and cap bars located over 115 the adjacent flanges of roof sheets and over the separator flanges, and at their extremities positioned under the running board and secured to the eave plates, respectively.

plates secured on the outer ends of the carlines and adapted to be secured to side plates, roof plates located on the stringers or purlines and having upwardly projecting flanges at their longitudinal edges, spacing flanges on the carlines between the flanges of the roof plates, cap bars located over the adjacent flanges of roof sheets and over the separator flanges, and at their extremities positioned under the running board and secured to the eave plates respectively, and cap plates located under the cap bars and having coupling relation to the inner ends of the roof plates, and at their inner ends located under the running board behind the flanges thereof.

6. A roof structure including metal carlines, a metal running board, metal roofing sheets having upturned inner edges, said running board secured to the carlines, depending flanges at the sides of the running board covering the upturned inner ends of the roof plates whereby a waterproof connection is made between the running board and the roof structure, and means holding the roof plates in proper assemblage and so associated therewith as to permit relative movement of said plates whereby the roof as a whole is capable of flexibility or independent movement of the parts. 20 25

ALFRED H. OELKERS.
